United States Patent Office

Des. 233,184
Patented Oct. 8, 1974

233,184

SIGN FACE PROTECTOR

Louis Alfonso, 207 Churchill St.,
Pittsfield, Mass. 01201

Filed Sept. 1, 1972, Ser. No. 285,869

Term of patent 14 years

Int. Cl. D20—99

U.S. Cl. D96—1

FIG. 1 is a front perspective view of the sign face protector showing my new design;

FIG. 2 is an end view thereof;

FIG. 3 is a rear perspective view thereof; and

FIG. 4 is a bottom view thereof.

I claim:

The ornamental design for sign face protector, as shown.
